(57) **CLAIM**

The ornamental design for the pillbox, as shown.

DESCRIPTION

FIG. 1 is a front perspective view thereof;

FIG. 2 is a front elevation view thereof;

FIG. 3 is a rear elevation view thereof;

FIG. 4 is a top plan view thereof,

FIG. 5 is a side elevation view thereof;

FIG. 6 is an opposite side elevation view; and,

FIG. 7 is a bottom plan view thereof.

The breaks in the drawing figures indicate indeterminate length.

The indicia shown in phantom on the lids plays no part in the design.
